HYDRAULIC PUMP OR MOTOR

Elek K. Benedek, Mount Gilead, Ohio

Application May 22, 1934, Serial No. 726,961

7 Claims. (CL 103—161)

This invention relates to pumps and motors of the radial piston type and has for particular object the provision of an improved structure which will be more efficient, easier to manufacture and assemble and disassemble, than pumps and motors of this type heretofore designed, and is a continuation in part of my prior application Ser. No. 716,451, filed March 20, 1934.

One of the main objects of this invention is the provision of means to obtain perfect alignment between the main relatively rotating parts (valve pintle and rotor) so that after assembly no frictional wear can take place between these parts, and consequently a longer useful life and greater hydraulic efficiency will be obtained.

Further objects of the invention include the provision of a novel arrangement of piston actuating parts whereby the replacement of pistons and piston crosspins is made feasible very easily by disassembling the piston actuating member, in order to exchange or replace worn or defective inner parts at minimum cost and time.

A further object lies in the application of standard interchangeable bearings for the piston actuating assembly to thereby facilitate easy repair and unrestricted production.

A further object of my invention is the elimination of frictional drag between the piston load carrying members and the piston crosshead connections to thereby eliminate heat, friction, and wear such as would be likely to cause loose crosshead connections and knocks in the mechanism.

A further object is the reduction of the number of parts in the piston crosshead connections with the operating reaction members to thereby reduce the radial dimensions of the mechanism when arranged to be used as a pump, and also the size of the crosshead actuating bearings, permitting increase in the running speed and also increase in the capacity of the pump, without increasing its overall dimensions and size.

A further object of the invention is the reduction of the axial dimensions of the pump, so that the valve support and main pump body may be cast in one piece, thereby facilitating accurate machining of the casting to effect concentric disposition, i. e. alignment, of the cylindrical bearing and pintle supports; more specifically, to facilitate manufacture and assembly by effecting as many machining operations as possible on the body parts without changing the parts from one machine to another, and so making the body parts that these parts must go together in a manner to maintain the cylindrical e. g. support

ing surfaces for the rotating elements in absolute alignment.

A further object is to provide a novel disposition of rotatable piston actuating elements close to the piston heads of opposite sides of the same, and the creation of novel means to properly mount said elements and accurately space them axially so as to provide an improved and precisioned anti-friction rolling path for the piston crosspins, thereby increasing the efficiency of the machine.

A further object is the provision of clamping means for piston actuating elements in the nature of anti-friction bearings, which means will be disposed circularly intermediately of the elements and align and mutually support the inner bearing race members to thereby provide ideal mountings for the actuating elements and effect rigidity of the piston actuating structure.

A further object is the provision in a hydraulic pump of means to positively locate the cylinder barrel or rotor against axial displacement, and prevent undue axial thrust on the barrel which might result from the use of an improperly designed coupling between the pump and its driving motor e. g. such as would be reason of axial thrust tend to close the necessary clearance between cylinder and valve and thus create too tight a fit therebetween and cause heat and wear and excessive dead load friction.

A further object is the novel application of coupling means between a cylinder block impeller and radial piston actuating relatively eccentric members of a pump of the class shown, to minimize load on the pistons and piston crossheads when the machine is set at maximum piston stroke and power output, thereby to increase the efficiency and useful life of the mechanism.

Other more specific objects and advantages will appear from the accompanying drawings and specifications.

In the drawings:

Fig. 1 is a horizontal sectional plan view of a pump embodying the novel characteristics hereof;

Fig. 2 is a transverse sectional view of the pump taken substantially along the line 2—2 on Fig. 1;

Fig. 3 is an end view of the novel cylinder block for the rotor looking toward the arrows 50 of line x—x Fig. 4; and

Fig. 4 is a longitudinal sectional view, partly in elevation of the novel cylinder block rotor, taken on line 4—4 on Fig. 3.

Referring to the drawings in detail, the pump

disclosed for illustration is enclosed within a liquid tight reservoir, comprising a main body member 1 having a generally cylindrical portion 1' and bell shaped central portion having a hub 2, the casing being completed by a bell shaped cover member 3 arranged to close the body member 1 of the casing in concentric relation thereto.

The rotor is mounted in the casing and comprises, as shown, a cylinder block forging 4 having a forged shaft portion 5 adapted for driving connection with a suitable source of motive power, such as an electric motor, Diesel engine etc. (not shown).

It being one of the principal objects of this invention to provide an efficient pump wherein the relatively rotating hydraulic parts are in precise alignment as to reduce wear, slip friction and undue depreciation of the device, the hub portion 2 is made very heavy and is accurately machined to rigidly support a cylindrical valve or pintle 10, which is tightly pressed into the bore of the hub as at 11. Further, in line with said object, I form the valve supporting hub 2 integral with the body portion 1 so that the bore for the pintle may be made at the same operation and tool-setting as counterbores 6 for the bearings 18 to be hereinafter described, as well as the cylindrical surface on the body portion 1 which locates the end cover 3 and bearings 19 supported thereby, also to be later described.

It will be seen that by the absolute concentricity of the pintle 10 the bearing 18 and end cover 3, through its concentric seat 8, the surfaces supporting the bearing 19 in the cover 3 will also be in a high degree of precision concentricity with the bearing 19, and thereby the entire rotor 4 and impeller shaft 5 will be mounted concentrically with the pintle 10, resulting in as nearly as possible, a frictionless mounting for the rotor 4 as well as true alignment and necessary uniform form fitting on all sides with the pintle 10.

In pumps of prior design, where the pintle 15 rigidly mounted in a separate valve end head, such accurate alignment could not be obtained, resulting in a less efficient and sturdy pump, due to misalignment of the rotational axis of the cylinder block and pintle axis and to crowding of bearings, and excessive wear and vibration took place; also excessive slip and low hydraulic efficiency. My novel structure eliminates such faults resulting from misalignment, by the simultaneous provision of pintle bore and end cover centering surface as at 8 in a one piece body casing.

The cylinder block forging 4 is provided with appropriate reduced portions (see Fig. 4) and thrust shoulders as at 4a, in order to positively take up thrust in two directions imposed respectively by the slight tapered fit of the pintle in the rotor and by the driving coupling attached to the shaft such as 5.

The bearing 19 has its inner race member 17 in contact with one of the thrust shoulders 4a to locate the rotor, and said race member is secured to the cylinder block or rotor 4 by a lock nut 43 threaded onto the rotor body so that the bearing 19 is locked positively to the rotor thus opposing any axial thrust on the rotor such as would widen or close the accurate hydraulic fitting relationship—close running clearance—between the pintle and rotor.

The concentricity or axial alignment of the bores 6 and 7 of the body members 1 and 3 further provides concentricity for the bores 6 and 7 respectively so that bearings 18 and 19 and the

rotor supported thereby will rotate accurately about the axis of the casing parts 1 and 3 and the axis of the pintle carried rigidly by and coaxially of the casing part 1, which conditions are of great importance from the standpoint of mechanical and volumetric efficiency of the pump.

The pintle 10 is provided with a suction port 12 and a pressure port 13 in a well known manner, which ports are reversible in action by a single straight line shift of the relatively eccentric mechanism, to be hereinafter described, which operates the pistons. The enlarged portion of the pintle 10 is further provided with inlet and outlet passages as at 14 and 15 respectively, which passages are connected respectively with the pump ports 12 and 13, pump mains being provided in the valve supporting hub 2 of the casing in the usual manner (not shown).

As hereinabove mentioned the supporting bore 11 for the pintle on the hub 2 is machined in the same tool-setting as that of counterbore 6 and centering surface 8 of the body casing to thereby make the axis of the pintle and the axis of the body casing 1 and 2 coincide. After this has been accomplished, the rest of the assembly will automatically assume proper alignment in the pump mechanism.

The cylinder block 4 in addition to pintle receiving concentric bores 10' and 11' is provided with a central spider flange as at 44 in the zone of the radial cylinder bores 22, which cylinders communicate with the barrel bore 10' through appropriate radial ports 22'.

Each individual cylinder 22 is fitted with a properly shaped piston 23 for radial reciprocation in the respective cylinder, for withdrawing operating fluid from one of the pintle ports 12 or 13 and discharging it into the other of said ports.

Each piston is provided with a flattened head portion 26 adapted to be guided radially in complementary radial ways 45 in the flange 44 of the forging 4 (see Figs. 3 and 4), the increased dimensions of the heads 26 in the zone of the flange being sufficient to take the transverse load component of the radial pistons which load component results from the relative eccentricity between the axis of the barrel 4 and the axis of the crosshead actuating elements 36 and 36' etc. these elements comprising, in part, ball bearing assemblies to be presently described. Such transverse load components are proportional to the eccentricity of the actuating assembly and stroke of the pistons and are greatest at full stroke and diminish as the eccentricity of the actuating elements and the stroke of the pump pistons approach zero, at which point there are no transverse strains on the pistons resulting from the hydraulic piston load. The complementary contacting surfaces of the piston heads 26 and ways 45 are preferably cylindrically generated as by a boring operation when the radial cylinders 22 are bored. These surfaces may however be non-circular (flat e. g.) if it is desired that the pistons be prevented from turning even slightly in the cylinders.

The general arrangement of adjustable piston actuating elements is as follows: An actuator supporting ring 41 is mounted to slide on suitable surfaces 41a and 41b, Fig. 2, machined in the cylindrical shell portion 1' of the casing part 1, actuation of the ring for adjustment of piston stroke and for reversal of the direction of flow of fluid through the pump being effected in more or less conventional fashion by suitable bars 40 and 40' extending into the casing from oppo-

site directions through suitable bores and secured as by threaded connections 39 and 39' to the ring 41. The inner surfaces of the ring are accurately machined to receive, as by slip fit, the outer race members 37 and 37' of the ball bearing assemblies heretofore mentioned, these being maintained in position against a central rib 42 forming shoulders for both members 37 and 37', by appropriate snap rings 38 and 38'. The balls 36 and 36' roll in the usual raceways of the outer and inner race members, the latter being indicated at 34 and 34' respectively.

The pistons are actuated inwardly by the inner surfaces of the inner race members 34 and 34' which contact directly with cross pins 25 carried in the heads 26 of the pistons as will now be described.

In order to further prevent wear and excessive friction between the heads 26 and the radial 20 guide surfaces 45 I provide anti-friction quill or needle bearings 24 and small crosspins 25 which due to the novel disposition of the crosshead actuating elements 36, 36' etc. thereto are subject to shearing stresses only, and are not only reduced in dimensions but also in mass, so that my novel pump and its pistons have substantially a minimum amount of reciprocating masses, compared to prior pumps of similar character, wherein there are large reciprocating masses. The reciprocating mass forces of the pistons and parts secured thereto are similar in effect to the mass forces imposed by piston rods, crossheads etc. of reciprocating engines and in radial piston type pumps become enormous at pump speeds such as 30 1000 to 2000 R. P. M. The improved crosshead assemblies herein shown and relative disposition thereof to anti-frictionally supported reactance means, and particularly the reduced length and masses of the piston assemblies marks a radical 40 departure from and improvement over pumps having relatively heavy shoes or sliding blocks or T-heads required to reciprocate at such high speeds as above mentioned.

Further noteworthy novelty of my invention resides in the provision of piston actuating rings 45 27 and 28, which serve two purposes: first they actuate the pistons during outward stroke by their lip portions 27' and 28' respectively—bearing directly on the cross pins—for positive displacement of the pistons outwardly, and, second, they serve as mountings for the bearing assemblies 36—36' etc. above described so that said inner race members in connection with said lip portions 27' and 28' form pairs of axially opposite circular grooves for the crosspins 25.

In order to secure rigid mounting for the bearing race members 36 and 36' I provide small flanges 33 and 33' on the rings 27 and 28, which locate the bearing members 36 and 36' positively 50 against axial separation. In order to set the axial distance of said bearings by the rings 27 and 28, I provide a circular series of hollow spacers 32 (Figs. 1 and 2) which determine that the axial distance between the bearings will be equal 60 to the width of the rib 42 of the control ring 41 against which the outer race members are maintained as described above. The rings 27 and 28 are clamped together in rigid relation to each other against the spacers 32 by suitable 65 screws 31, corresponding in number to the spacers and passing through registering openings in the rings 27 and 28, being threaded into one of the rings as at 31' and having heads 31'' abutting the other of said rings. The screws may be locked 70 in position in any suitable manner. The spacers

are of sufficient length to provide, between the rings 27 and 28 definite clearance spaces for the piston heads between the inwardly disposed surfaces of the race members 34 and 34' and the rings 27 and 28. The clearance is somewhat exaggerated on the drawings for clearness of illustration. When the ring securing and clamping screws 31 are set and locked, the small flanges 33 and 33' exert sufficient force inwardly on the inner bearing race members to take up all unnecessary play and these small flanges thus cooperate with the shoulders on the rib 42 and with the snap rings 38 and 38' to hold the bearing race members positively in freely operating alignment but against axial displacement in either direction. Nevertheless the parts of the relatively eccentric mechanism are capable of being easily and quickly assembled and later disassembled—as for inspection, replacement or repair of parts—in an obvious manner.

In addition to the clamping and mounting purposes of the screw and sleeve arrangement 31, 32 above described these parts in connection with the rotor forging serve as positive driving coupling elements between the relatively eccentric 25 piston actuating mechanism and the rotor during certain conditions as will now be described.

In my novel cylinder block forging the flange portion 44 is provided a plurality of circumferentially deployed axial openings or holes 30, one between each two radial guide ways 45 in order to provide free passage for the screws 31 and spacers 32 from the ring 27 to the ring 28. Since however the path of every point of the cylinder block 4 relative to the piston actuating assembly 35 is a circle struck around the point in question with a radius corresponding to the extent of eccentricity of the actuating assembly at any setting thereof, it is evident, that a circle, struck about the axis of the members 31 ample to provide circular clearance for the members 31 in the maximum eccentric position of the actuating assembly, must be on a radius at least equal in length to the maximum eccentricity of the pump. By providing exactly this clearance then at maximum eccentricity and stroke the relatively eccentric mechanism comprising the bearings 36, 36' etc. and rings 27, 28, will be positively driven by the impeller barrel 4 and consequently at this maximum power transmission of the pump, the cross pins 25 will be unloaded from excessive friction and wear incident to transmitting the driving torque from the piston cross pins to the annular surfaces of the rings 27 and 28 or the inner bearing race members as the case might be.

At shorter strokes than maximum my novel structure will, upon initial operation, provide positive starting of the entire rotary assembly of the pump, and thus prevent the cross pins 25 from racing with excessive speed in their annular tracks.

So far as I know such positive driving coupling connection between the relatively eccentric parts at maximum stroke of the pistons, relieving the pistons from having to transmit the driving 65 torque, is entirely new in a mechanism of this class, likewise I believe the compact arrangement of parts is entirely new.

I claim:

1. In a pump or motor of the character described, a casing, a rotor and supporting bearings therefor in the casing, a valve pintle in the casing disposed coaxially with said rotor and casing, relatively eccentric mechanism slidably mounted in said casing and including a ring 70 75

and sliding support therefor in the casing, anti-friction bearings in said ring axially separated to provide a clearance space between said bearings, the rotor having radial guide ways and piston heads in said ways between said bearings in said clearance space, each head carrying a cross pin extending axially of the rotor, a piston associated with each piston head, a cylinder for each piston carried by said rotor and adapted to communicate with the valve, a mounting ring for each bearing inside thereof recessed to provide respective circular grooves one between each bearing and mounting ring to receive the piston actuating pins, coupling members disposed circumferentially between adjacent pistons to positively couple said mounting rings and maintain said bearings against axial displacement, and means carried by the rotor and positioned to engage the spacing means to effect a driving connection between said rotor and said relatively eccentric mechanism.

2. In a pump or motor of the character described, a casing, a piston carrying rotor journaled axially in the casing, relatively eccentric mechanism surrounding the rotor and disposed within the casing for operating pistons carried by the rotor, said mechanism comprising an outer ring member mounted in the casing, anti-friction bearing assemblies including inner and outer race members in spaced relation to each other, said assemblies being mounted within the outer ring, inner ring members each having flanges lying axially outwardly from said bearing assemblies to retain the inner races against axial separation, said inner ring members cooperating with the inner race members of said bearing elements to provide circular track ways, means rigidly securing said inner ring members together with the flanges in clamping relation to the inner race members of the bearings, and means carried by the pistons extending laterally therefrom into operative engagement with said circular tracks for actuation thereby on rotation of the rotor.

45 3. In a pump or motor of the class described, a casing, a rotor therein, piston and cylinder assemblies carried by the rotor, bearing means supporting the rotor, valve means rigidly mounted in the casing and cooperatively associated with the piston and cylinder assemblies of the rotor, relatively eccentric mechanism mounted in the casing, said mechanism comprising an outer ring, antifrictional bearings in the ring axially separated to provide an intervening space between them, the outer ends of the pistons extending into said intervening space, thrust means carried by the pistons operatively engaging the inner surfaces of said bearings for inward movement of the pistons, a mounting ring for each of said bearings inside thereof and circularly recessed to operatively receive said piston thrust means and provide a track surface for effecting positive outward movement of the pistons, and means rigidly coupling said mounting rings, said outer ring having inwardly extending means axially abutting said bearings and spacing the same, the coupling means and mounting rings cooperating to hold the bearings in abutment with said abutting and spacing means.

70 4. In a pump or motor of the character described, a casing, a rotor rotatably mounted in the casing and having a plurality of radial cylinders, valve means for the cylinders, relatively eccentric reactance means mounted in said casing and including a support in the casing, anti-fric-

tion bearing assemblies in said support and axially spaced to provide a clearance space between said bearing assemblies, pistons in the cylinders having piston heads accommodated between said bearing assemblies in said clearance space, each head carrying thrust means extending axially of the rotor beyond the associated head, mounting rings for the bearing assemblies fixedly mounted inside thereof and recessed to provide with the assemblies grooves between the bearing assemblies and the associated mounting rings to receive the piston thrust means in direct load transmitting engagement with the assemblies, and means constraining each bearing assembly and associated mounting ring from axial displacement relative to the other bearing assembly and associated mounting ring.

5. In a pump or motor of the character described, a valve pintle, a cylinder barrel mounted for rotation about said pintle and being formed with a plurality of circumferentially spaced radially disposed cylinders, pistons reciprocable respectively in said cylinders, a reactance device mounted eccentrically with respect to said cylinder barrel, said reactance device including rotatable axially spaced members each formed with a continuous circular trackway and each having a radial portion, said cylinder barrel having a radial portion disposed between said spaced members, and said pistons respectively having outer portions disposed between said spaced members, thrust-transmitting means connected to each piston outer portion and operatively engaging the circular trackways of said reactance device spaced members on opposite sides of the piston outer portions, and circumferentially deployed cylindrical coupling and spacing means extending parallel to the axis of said barrel and connecting said reactance device members together in fixed spaced relation, said cylinder barrel radial portion being formed with circumferentially deployed cylindrical openings extending parallel to the barrel axis and through which said coupling and spacing means extend respectively, the difference between the diameters of said openings and the diameters of said coupling and spacing means being at least equal to the eccentricity of said reactance device relative to said cylinder barrel.

6. In a pump or motor of the character described, a plurality of rotatable radially disposed piston and cylinder assemblies each comprising a relatively reciprocable part and a relatively nonreciprocable part; a reactance device eccentrically disposed with respect to said assemblies and comprising axially spaced anti-friction bearing assemblies each including an outer race and an inner race and a plurality of interposed anti-friction elements, two reactance rings, one associated with each of said bearing assemblies, each ring having a portion underlying and engaging a part only of the associated inner race and another portion underlying but being spaced inwardly from the remaining part of said inner race to provide a resultant arcuate track groove, the track groove thus formed by each inner race and associated ring facing and opening towards the similar groove formed by the other inner race and ring; and thrust-transmitting means extending through said relatively reciprocable elements and into said track grooves and operatively and directly engaging said inner races.

7. In a pump or motor of the character described, a plurality of rotatable radially disposed piston and cylinder assemblies each comprising

a relatively reciprocable part and a relatively nonreciprocable part; a reactance device eccentrically disposed with respect to said assemblies and comprising axially spaced anti-friction bearing assemblies each including an outer race and an inner race and a plurality of interposed anti-friction elements, two reactance rings, one associated with each of said bearing assemblies, each ring having a portion underlying and engaging a part only of the associated inner race and another portion underlying but being spaced inwardly from the remaining part of said inner race to provide a resultant arcuate track groove, the track groove thus formed by each inner race

and associated ring facing and opening towards the similar groove formed by the other inner race and ring, said relatively reciprocable members having portions projecting between said rings and between adjacent side surfaces of said inner races, said rings having flanges respectively engaging the remote side surfaces of said inner races to maintain said inner races against axial movement away from each other; and thrust-transmitting means extending through said relatively reciprocable elements and into said track grooves and operatively and directly engaging said inner races. 5 10
